TRAVEL TOTE

Edward J. Hill, 1660 Lochridge Road,
Bloomfield Hills, Mich. 48013

Filed Nov. 9, 1973, Ser. No. 414,317

Term of patent 14 years

Int. Cl. D8—06

U.S. Cl. D8—154

FIG. 1 is a side elevational view of a travel tote showing my new design, the side opposite being a mirror image thereof; and

FIG. 2 is a front elevational view taken on the line 2—2 of FIG. 1.

I claim:

The ornamental design for a travel tote, substantially as shown.
